5 Claims. (Cl. 260—556)

The present invention relates to new N-vinylamides and to a process for preparing them; more particularly, it relates to compounds of the formula

wherein R_1 represents a methyl or ethyl group and R_2 stands for a methyl, ethyl or propyl group.

It is known that carboxylic acid and sulfonic acid amides of primary amines carrying another hydrogen atom at the amide nitrogen and lactams having an unsubstituted nitrogen atom can be converted in the presence of strongly alkaline catalysts with acetylene, under pressure, into the corresponding N-vinyl compounds.

This vinylation process for amides has hitherto been carried out under pressure only. Because of the risks which exist when working with compressed acetylene, expensive high pressure armatures are necessary for such a process, even when operating under pressures slightly above one atmosphere.

Furthermore, with this known pressure vinylation a smooth conversion takes place with cyclic lactams only. When applying the pressure process to acyclic, aliphatic carboxylic acid amides of the type of the N-methylacetamide and its homologues, the vinylation comes to a standstill after a low conversion. So, for example, with pressure vinylation only 28% of N-vinyl-methylacetamide is obtained from N-methylacetamide. Besides, undesired tarry products are sometimes formed to a large extent by side reactions when acyclic amides are subjected to a pressure vinylation, whereby the yield and economy of the process are strongly impaired.

Now we have found a process for preparing N-vinylamides from acetylene and amides of the formula

in which R and R' represent aliphatic, cycloaliphatic, araliphatic or aromatic radicals, in which R and R' may also be linked together to form a ring and in which Y stands for the carbonyl group $-\text{CO}-$ or the sulfonyl group $-\text{SO}_2-$, in liquid phase in the presence of basic catalysts, wherein the reaction is carried out at a pressure between about 1 and 2.5 atmospheres and the vinylamide which is formed is removed from the reaction zone as it is formed. It was surprising that the vinylation, which is known to be carried out under high pressures only, can be practised at pressures within the range of one atmosphere or substantially lower. On the other hand, it was surprising that the longevity of the catalyst can be increased in the process of the present invention to such an extent that the conversion is almost quantitative with acyclic amides, too.

In the carboxylic acid amides of the formula

the N-vinyl derivatives of which are sufficiently volatile under the reaction conditions, R and R' represent equal or different, straight chain or branched, aliphatic or also isocyclic hydrocarbon radicals which have generally 1

2

to 12 and preferably 1 to 7 carbon atoms and which, in the case of isocyclic radicals, have preferably 5 to 6 carbon atoms in the ring. R and R' may be linked together so that the starting compound is a cyclic carboxylic acid amide having preferably 5 to 7 ring members.

Compounds which are capable of being vinylated, according to the process of the present invention, are, for example, N-methylacetamide, N-ethylacetamide, N-butyacetamide, N-methylpropionamide, N-ethylpropionamide, 10 N-propylpropionamide, N-methylisobutyramide, N-butybutyramide, N-methyl-trimethylacetamide. Higher aliphatic homologues such as N-methylauric acid amide or N-dodecylacetamide may be successfully vinylated, too. Furthermore, there are suitable N-cyclohexylacetamide, 15 N-methyl-hexahydrobenzamide, N-methylbenzamide, acetanilide. Suitable lactams are pyrrolidone-2, piperidone-2 and ϵ -caprolactam and their derivatives substituted at the carbon atom by low molecular weight alkyl radicals.

20 Suitable sulfonic acid amides of the formula

wherein R and R' have the meaning given above are, for example, N-methyl-methane-sulfamide, N-methyl-ethane-sulfamide and N-ethyl-propane-sulfamide.

As basic catalysts there are suitable, above all, alkali metals such as sodium and potassium and strongly basic compounds thereof such as sodium hydroxide, sodium amide, sodium methylate, sodium ethylate, sodium hydride, potassium hydroxide, potassium-tertiary-butylate. Particularly active are the alkali metal compounds of the amides used as starting compounds. In the conversion of N-methylacetamide, for example, there is preferably used sodium-N-methylacetamide and in the conversion of pyrrolidone-2 the potassium salt of the pyrrolidone-2. The alkali metal compound of the amides is preferably prepared in situ by dissolving one of the afore-mentioned alkali metal compounds in the amide to be vinylated.

For carrying out the process, excess acetylene is advantageously passed through the liquid mixture of the catalyst with the corresponding amide and heated to a temperature within the range of 90° and 300° C., preferably 150° and 250° C. The reaction temperature is suitably selected so that the N-vinylamide which forms is removed from the reaction mixture as quickly and completely as possible while the amide used as starting compound is substantially retained. Thus the optimum temperature to be maintained in the zone of vinylation and the velocity of the gas current passed through are dependent on each other within certain limits. The vapors, which leave the reaction vessel together with the acetylene not used up, are condensed. From this condensate the N-vinylamide and unreacted starting amide are isolated by distillation, under reduced pressure if necessary, or by extraction or crystallization processes.

The process may be carried out batchwise, or in semi-continuous or continuous manner. The unreacted acetylene freed from condensable vapors is suitably recycled into the process while adding fresh acetylene. In the same manner, the unreacted starting amide can be continuously returned into the vinylation zone. Both the excessive acetylene and the unreacted starting amide, which is separated by a continuous distillation column, are preferably returned in a continuous manner into the vinylation zone, if necessary after previous mixing. In this case, the amount of fresh starting products corresponding to the amount of reacted acetylene and amide is additionally supplied in a continuous manner.

70 The catalyst is generally used in an amount ranging from 0.1 to 20 mol percent, preferably 1.0 to 10 mol percent, calculated on the amide used. With a continuous

operation, it is often suitable to introduce part of the catalyst together with the amide supplied in a continuous manner.

The acetylene may be used in pure form or in admixture with inert gases, for example nitrogen.

The process is preferably carried out at atmospheric pressure. In exceptional cases it may be of advantage to work under slightly elevated pressure, for example up to 2.5 atmospheres gauge. With regard to the severe safety measures required for pressure reactions with acetylene, however, efforts are made to keep the excess pressure as low as possible. In some cases, especially when high boiling amides are used, it may be suitable to work under reduced pressure.

Because of improved yield, the process of the present invention permits a more economical preparation of acyclic vinylamides than is possible with prior art processes. A particular advantage is that pressure apparatus and safety measures which are required when working with compressed acetylene need not be used. Thus, vinylamides have become easily accessible. The method is also suitable for working on a laboratory scale. Some products according to the present process are novel substances, viz N-vinyl-N-ethylacetamide, N-vinyl-N-methylpropionamide, N-vinyl-N-ethylpropionamide and N-vinyl-N-methylisobutyramide.

The vinylamides are valuable starting materials for plastics, emulsion stabilizers, textile auxiliaries, cosmetics, pesticides and pharmaceutical products.

The following examples serve to illustrate the invention but they are not intended to limit it thereto. Prior to beginning the tests, all apparatuses were freed from oxygen by purging with nitrogen.

Example 1.—N-vinyl-N-methylacetamide

(a) In a four-neck flask provided with stirrer, gas inlet pipe, internal thermometer and a condensing tap, a current of 150 liters per hour of acetylene was passed, at 180° C. and at normal pressure, while vigorously stirring, through a solution of 4.5 g. of potassium-N-methylacetamide in 295.5 g. of N-methylacetamide prepared by dissolving 1.6 g. of potassium in 298.4 g. of N-methylacetamide. Within 90 minutes there were obtained 294.4 g. of a condensate from which 35.2 g. of N-vinyl-N-methylacetamide were obtained by distillation under reduced pressure. Boiling point at 20 mm. of mercury=63.8° C.; $n_D^{20}=1.4827$. 258 g. of unchanged N-methylacetamide were recovered, while 12.5 g. of residue remained in the reaction flask.

(b) A heatable multineck flask provided with stirrer, gas inlet pipe, internal thermometer and a supply pipe reaching down to the bottom was connected via a well isolated vapor pipe with a separator from which the gases coming out of the flask could escape upward to an effective cooler. The condensate flowed downwards to the middle of a suitably dimensioned distilling column having a total height of 80 cm. The sump product leaving this column flowed back through the feed pipe into the reaction flask. Through the same pipe the supply of N-methylacetamide was replenished from a dropping funnel in proportion to its conversion. The N-vinyl-N-methylacetamide was collected at the head of the distilling column. The acetylene leaving the separator and the cooler was recycled through the inlet pipe into the reaction flask by means of a gas pump, the consumed gas being replenished and a little part being let off as exhaust gas. 2.00 kg. of N-methylacetamide were introduced into the reaction flask in which 20 g. of sodium amide had previously been dissolved while pumping off the ammonia. Through the mixture heated to 170° C., there were passed 600 liters of acetylene per hour, at about normal pressure. During the course of 30 hours, there were added thereto a total of 3.88 kg. of N-methylacetamide in which 150 g. of sodium amide had previously been dissolved

with degassing, while 4.58 kg. of N-vinyl-N-methylacetamide of 99% strength distilled off at the head of the column. The test was then discontinued without the vinylation being abated. For calculating the conversion, the content of the reactor and the sump of the column (2.57 kg.) were distilled whereby 1.57 kg. of methylacetamide were recovered.

Considering the fact that 0.31 kg. of the methylacetamide used were bound in the catalyst, the conversion amounted to 72% and the yield to 85% of the theoretical.

Example 2.—N-vinyl-N-ethylacetamide

In the apparatus described in Example 1a, there were passed, at 190° C., and at about 1 atmosphere, 100 liters of acetylene per hour through a reaction mixture obtained by dissolving 1.8 g. of sodium in 341 g. of N-ethylacetamide. There were obtained 320 g. of condensate which yielded by distillation 27 g. of N-vinyl-N-ethylacetamide having a boiling point at 18 mm. of mercury of 69° C., ($n_D^{20}=1.4750$).

Analysis.— $C_6H_{11}NO$ (113.2) calculated: C, 63.7; H, 9.8; N, 12.4. Found: C, 63.5; H, 9.4; N, 12.5. By catalytic hydration, diethylacetamide was obtained therefrom.

Example 3.—N-vinyl-N-methylpropionamide

In the apparatus described in Example 1a, there was passed, at 190° C., and at about 1 atmosphere, a current of 150 liters of acetylene per hour through a solution of 2.3 g. of sodium in 435 g. of N-methylpropionamide. From the condensate (421 g.) were obtained 47 g. of N-vinyl-N-methylpropionamide. Boiling point at 13 mm. of mercury=69° C.; $n_D^{20}=1.4797$.

Analysis.— $C_6H_{11}NO$ (113.2) calculated: C, 63.7; H, 9.8; N, 12.4. Found: C, 64.0; H, 9.9; N, 12.4.

Example 4.—N-vinyl-N-ethylpropionamide

By the same process as described in the foregoing examples, there were obtained from a solution of 2.3 g. of sodium in 505 g. of N-ethylpropionamide, at a temperature ranging from 190 to 200° C., with an acetylene current of 150 l./h., 494 g. of distillate which yielded 69 g. of N-vinyl-N-ethylpropionamide. Boiling point at 12 mm. of mercury=74° C.; $n_D^{20}=1.4737$.

Analysis.— $C_7H_{13}NO$ (127.2) calculated: C, 66.1; H, 10.3; N, 11.0. Found: C, 66.2; H, 10.1; N, 11.0.

Example 5.—N-vinyl-N-methyl-isobutyramide

A solution of 2.3 g. of sodium in 505 g. of N-methyl-isobutyramide was gassed, as described in Example 1a, at a temperature ranging from 180° to 190° C. with 150 l. of acetylene per hour at about normal pressure. 491 g. of distillate passed over from which there were isolated 54 g. of N-vinyl-N-methylisobutyramide. Boiling point at 19 mm. of mercury=75° C.; $n_D^{20}=1.4739$.

Analysis.— $C_7H_{13}NO$ (127.2) calculated: C, 66.1; H, 10.3; N, 11.0; hydrogenation iodine number 200. Found: C, 66.0; H, 10.2; N, 11.8; hydrogenation iodine number 205.

Example 6.—N-vinyl-N-methylbenzamide

After having pumped off the ammonia formed, a solution of 4.7 g. of sodium amide in 405 g. of molten N-methylbenzamide was treated, as described in Example 1a, at a temperature within the range of 220 and 230° C. with an acetylene current of 300 l./h. at about normal pressure. The condensate (319 g.) yielded by distillation under reduced pressure 94 g. of N-vinyl-N-methylbenzamide. Boiling point at 14 mm. of mercury=137 to 139° C.; $n_D=1.5670$.

Example 7.—N-vinylpyrrolidone

In the apparatus described in Example 1 200 liters of acetylene were passed, at a temperature within the range of 210° to 230° C. and at about 1 atmosphere through a solution of 6.3 g. of sodium in 425 g. of pyrrolidone-2 until no more amide passed over. The condensate (392 g.)

contained 36% of N-vinylpyrrolidone. In the distillation were obtained 145 g. of pure N-vinylpyrrolidone. Boiling point at 10 mm. of mercury=92-93° C.; $n_D^{20}=1.5113$.

Example 8.—N-vinyl-N-methyl-methane-sulfamide

600 liters of acetylene per hour were passed at 200° C. and at about 1 atmosphere, and as described in Example 1a, through a solution of 64.5 g. of sodium-N-methyl-methane-sulfamide (0.5 mol) in 1015 g. of N-methylmethane-sulfamide (9.3 mol), prepared by dissolving 11.5 g. of sodium in 1070 g. of N-methylmethanesulfamide. Within 4½ hours, 1026 g. of condensate passed over, while 80 g. of substance remained undistilled. From the condensate there were obtained by distillation under reduced pressure, in addition to 699 g. of starting amide, 291 g. of pure N-vinyl-N-methyl-methane-sulfamide. Boiling point at 10 mm. of mercury=99° C.; $n_D^{20}=1.4701$. This result corresponded to a conversion of 31% and a yield of 75%.

Analysis.— $C_4H_9NO_2S$ (135.2) calculated: N, 10.4; S, 23.7; hydrogenation iodine number 188. Found: N, 10.7; S, 23.5; hydrogenation iodine number 188.

Example 9.—N-vinyl-N-ethylacetamide

The apparatus described in Example 1b was charged with 1000 g. of N-ethylacetamide in which 14.5 g. of sodium amide were dissolved while the ammonia set free was removed. 700 liters of acetylene per hour were passed at 170° C. and at about normal pressure through the mixture. During 43 hours there were added a further 4.67 kg. of ethylacetamide in which 163 g. of $NaNH_2$ were dissolved, and 4.49 kg. of N-vinyl-ethylacetamide were distilled off at the same time. From time to time a portion of the reactor content was removed in order to avoid a concentration of the sodium salts. From these quantities and the remaining reactor content, there were recovered 1.44 g. of ethylacetamide. Thus, the conversion was 75% and the yield amounted to 82%.

Example 10.—N-vinyl-N-methylpropionamide

In the same manner as described in Example 1b and 9, there were prepared in 34 hours, from 4.66 kg. of N-methylpropionamide and 118 g. of sodium amide, 2.96 kg. of N-vinyl-N-methylpropionamide in a reactor having a content of 1 l., at a reaction temperature of 175° C. and an amount of 700 liters of acetylene per hour. 1.34 kg. of starting amide were recovered. Conversion: 72%; yield: 69%.

Example 11.—N-vinylpyrrolidone

According to the processes described in Examples 1b, 50 9 and 10, there were obtained in 27 hours, from 6.07 kg. of pyrrolidone and 80 g. of sodium amide, 4.47 kg. of N-vinylpyrrolidone at 190° C. and with 1050 liters of acetylene per hour. 1.79 kg. of pyrrolidone were recovered. Thus, the conversion amounted to 70% and the 55 yield to 80%.

Example 12.—N-vinyl-N-isopropylacetamide

As described in Examples 1b, 9, 10 and 11, the solution of 110 g. of sodium amide in 3.79 kg. of N-isopropylacetamide was reacted at 170° C. and with a circulation of 600 liters of acetylene per hour. 2.175 kg. of starting

amide were recovered and 1.12 kg. of N-vinylisopropylacetamide were obtained. The result corresponded to a conversion of 42% and to a yield of 55%. Boiling point at 15 mm. of mercury=69° C.; $n_D^{20}=1.4645$.

We claim:

1. In a process for preparing compounds of the formula

10 wherein X is a member selected from the group consisting of carbonyl and sulfonyl, R_1 is lower alkyl, R_2 is a member selected from the group consisting of lower alkyl and phenyl, and R_1 and R_2 together are lower alkylene, which process comprises reacting acetylene with an amide of the formula

15 wherein R_1 , R_2 , and X are defined as above, in liquid phase and in the presence of a basic catalyst, the improvement of passing gaseous acetylene at a pressure between 1 and 2.5 atmospheres through said amide and removing the N-vinylamide product from the reaction zone in vapor form as it is formed.

20 2. A process as claimed in claim 1, wherein the reaction is carried out at a temperature between 150° and 250° C.

25 3. A process as claimed in claim 1, where in an alkali-metal salt of the amide employed as starting material is used as catalyst.

30 4. A process as claimed in claim 1, wherein unreacted acetylene and unreacted amide escaping from the reaction zone are continuously recycled to the reaction zone.

35 5. A process as claimed 1, wherein the catalyst is used in amounts between 1.0 and 10 mol percent, calculated on the amide used.
